UNITED STATES PATENT OFFICE.

BRENTON E. HOLLY, OF FULTON, NEW YORK.

THILL-SUPPORT.

SPECIFICATION forming part of Letters Patent No. 615,066, dated November 29, 1898.

Application filed August 19, 1898. Serial No. 688,988. (No model.)

To all whom it may concern:

Be it known that I, BRENTON E. HOLLY, a citizen of the United States, and a resident of Fulton, in the county of Oswego, in the State of New York, have invented new and useful Improvements in Thill-Supports, of which the following, taken in connection with the accompanying drawings, is a full, clear, and exact description.

10 This invention relates to the class of thill-supporters which are employed for holding the thills in upright position when the vehicle is not in use; and it has special reference to the species of supporters which have 15 their members pivoted to fold compactly when not in use.

The object of this invention is to provide a thill-supporter which shall be simpler and less expensive in construction and shall obviate the liability of marring or defacing the parts of the vehicle on which the supporter is caused to bear when in use; and to that end the invention consists in the improved construction and combination of the component 25 parts of the thill-supporter, as hereinafter described, and pointed out in the claim.

In the annexed drawings, Figure 1 shows my improved thill-supporter in operation, and Fig. 2 is an enlarged side view of the 30 same in its folded condition.

a denotes the arm by which the thill-supporter is connected to the vehicle, and *b* the brace by which it supports the thill in upright position, as shown in Fig. 1 of the drawings. Said arm and brace are both formed 35 of wood to obviate marring or injuring the surfaces of the parts of the vehicle which said members of the supporter come in contact with when in use. The attaching-arm *a* is placed astride either the head-block *c* or cross-spring *d*, according to the style of vehicle to 40 which the supporter is applied.

The rear end of the arm *a* is curved upward to bear directly on the under side of the

body *e* of the vehicle, and thus enable said 45 arm to support the thills in upright position by the brace *b*, which projects upward from the front end of the arm and engages the front of the cross-bar *t* of the elevated thills. The brace *b* is connected to the arm *a* by 50 metal straps *f*, pivoted at one end to the said arm and at the opposite end to the brace to allow said brace to be folded back upon the arm when not in use, as represented in Fig. 2 of the drawings. To sustain the brace in its 55 upright position, as shown in Fig. 1 of the drawings, the front end of the arm *a* is formed with a notch *a'*, in which the foot of the brace rests, said notch affording both a bottom bearing and a side bearing for the brace. To prevent the arm *a* from slipping forward when in use, I cut in the under side of said arm one or more notches *h*, engaging the rear of the part of the vehicle upon which said arm rests. The wooden faces of the engaged notch obviate 65 marring the surfaces in contact therewith.

My invention resides, first, in the curvature of the arm *a*, permitting said arm to bear directly on the under side of the vehicle-body; secondly, in the notches *h*, cut in the under 70 side of the said arm, and, thirdly, in the notch *a'* in the end of the arm for supporting the brace *b*, all of which features render the thill-supporter very simple and inexpensive in construction and efficient in operation.

What I claim as my invention is—

The improved thill-supporter consisting of the arm *a* curved upward at its rear end and having notches *h* cut in its under side and the notch *a'* in its front end, the brace *b* seated 80 in said end notch, and the straps *f* pivoted at one end to the aforesaid arm and at the opposite end to the brace substantially as described and shown.

BRENTON E. HOLLY. [L. S.]
